SURPRISE DISPLAY.

Guy E. Ditzler, Brookfield, and Maurice B.
Kovnat, Chicago, Ill.

Application February 24, 1947, Serial No. 730,476

1 Claim. (Cl. 40—126)

1

This invention relates to a folding display activated by resilient means such as rubber bands to spring from a compactly folded position to an upright erected position, usually representing some article or figure and thus constituting an advertising or display device.

An important object of the invention is to provide a new and improved folding display of this kind in which side portions as well as an upright or erect front portion are extended to provide a three dimensional structure in its display or erected position.

A further object of the invention is to provide a surprise display adapted to be sent as a mailing piece in folded condition such that upon opening the enclosure, the folded portion will spring upwardly into erected position, thereby providing a simple, lightweight advertising device which may be made in various shapes and forms to represent erected structures which may themselves constitute an advertised device or may provide a medium for calling attention to the devices which it is intended to advertise.

Other objects of the invention will appear in the specification and will be apparent from the accompanying drawings in which,

Fig. 1 is a perspective view of a folded surprise display in accordance with this invention;

Fig. 2 is a perspective view of the structure shown in Fig. 1 in display or erected position;

Fig. 3 is a sectional view taken on the line 3—3 of Fig. 1;

Fig. 4 is a sectional view taken on the line 4—4 of Fig. 2;

Fig. 4^a is a fragmentary sectional view taken on the line 4^a—4^a of Fig. 1.

Fig. 5 is a perspective of another surprise display in accordance with this invention in its erected form;

Fig. 6 illustrates the display of Fig. 5 in folded position and as contained within an ordinary envelope shown by dotted lines; and

Fig. 7 is a sectional view taken on the line 7—7 of Fig. 6.

Surprise displays activated by rubber bands have heretofore been proposed comprising a jointed figure which is raised from a folded position upon a supporting card, but the present invention proposes to provide a three dimensional figure which is raised from a flat folded position, thus providing for an increased number of display structures which may be utilized for a variety of advertising and display uses.

Referring now more particularly to the drawings, the folding structure is mounted upon a

2

supporting base 10 of flexible light-weight material such as cardboard and usually of a size to be included in an ordinary mailing envelope.

Upon this base, the folding structure is secured 5 adhesively or in any other suitable manner, usually adjacent one end although it may be located at any desired place, depending upon the display.

The folding structure may also be of card- 10 board, and in fact may be a continuation of the base consisting of a portion 11 folded inwardly from one end of the base 10 and adhesively secured thereto or by staples 12. Extending as a 15 continuation of the portion 11 is a front 13 of the display connected to the bottom by fold line 14 with sides 15 connected to the front by fold lines 16.

A display top 17 forms a continuation of the 20 display front 13 connected thereto along a fold line 18.

Extending as a continuation of the top is a 25 rear upright 19 for the display connected thereto by an extension piece 20. The extension piece 20 is connected to the upright 19 upon a fold line 21 and to the top portion 17 by fold line 22 and the side edges of the portions 19 and 20 have angular cuts 23 and 24 respectively fold- 30 able together and extending below the top 17 in the raised position of the display.

Connecting each of the sides 15 with the top portion 17 is an angular folding portion 25. One edge of the angular portion 25 is connected 35 with the side 15 by a fold line 26. Another edge of the angular portion is connected to the top portion 17 by a fold line 27 and intermediate these two fold lines is an angular fold line 28. The fold lines 18 adapt these triangular portions to fold inwardly when the display is erected, thus constituting a support for the top 40 17. The angular cuts 23 and 24 adapt the rear upright and its connecting portion 20 to fold compactly at the ends of the angular connecting portions 25 as clearly shown in the folding position in Fig. 1.

In order to activate the display, a rubber band 45 30 of the endless variety is connected to the base, the sides 15 and to the rear upright 19 by providing openings 31 near the edge of the base 10 and outside of the connected portion 11 into which the band 30 may be inserted through 50 cuts 32 extending from the edge of the base to the openings 31; by similar openings 33 near the lower edges of the sides 15 connected to the edges thereof by cut slits 34; and by openings 35 in the rear upright 19 and its connecting ex-

tension piece 20 connected to the adjacent edges thereof by cuts 36. The broken lines in Fig. 1 show the extension piece 20 and the rear upright 19 in unfolded extending position before they are folded together in partially overlapping condition as indicated more clearly in Figs. 4 and 4^a. When so overlapped, these portions (19 and 20) are held together by the rubber band 30 which is hooked into the registering openings 35 of these two pieces as shown in Fig. 1. Intermediate the openings 33 and 35, the rubber band is crossed, that is, it extends from the opening 33 of one side to the opening 35 of the other side, with the result that when the display is released from the folding position as shown in Fig. 1, the rubber band will tend to swing the entire folding structure upwardly with respect to the base 19 upon the fold line 14, and at the same time as the folding structure is swung upwardly, the sides 15 will be swung outwardly. At the same time the top 17 will be folded on the fold line 18 and the rear upright will be swung into upright position upon its fold line 22. Cross connection of the strands of the rubber band 30 is not absolutely necessary but the sides are swung more definitely to their outer position and the surprise action of the display is more quick and snappy than if the bands are not crossed.

With this construction, the display device when unfolded and extended constitutes substantially a continuation of one end of the base 10 and all of the outer sides of the display device and of the top 10 of the base may be simultaneously printed, which is a considerable value from a cost standpoint if a large number of the display devices are to be produced.

Another form of this display is shown in Figs. 5, 6 and 7 wherein a semi-cylindrical figure is erected upon a base 51. This display may also be made of one piece of material printed upon one side only and comprising a bottom portion 52 having rounded side edges 53 connected at the front by a hinge 54 with a front piece 55 constituting the curved surface of the semi-cylindrical figure. It has sides 56 foldable upon hinges 57, and near the edges of the sides are openings 58 each connected to the adjacent edge by slits 59. At the top of the front piece 55 is a hinge 60 connecting it with a semi-circular top piece 61 having a hinge 62 connecting it with a back piece 63 of substantially the same height as the front piece 55. At the bottom of the back piece 63 is a semi-circular bottom piece 64 foldable upon a hinge 65 and adhesively or otherwise secured to that portion of the bottom piece 52 having the rounded edges 53.

To activate this display, a rubber band 66 is inserted into the openings 58 through the slots 59, the intermediate portions of the band are crossed, and the other extremity is inserted into the openings 67 near the rear edge of the base 55 through slits 68.

As soon as this folding display is released from an envelope 70 in which it is enclosed, the rubber

band activator will pull the display upwardly from the base 55 erecting the display to the position shown in Fig. 5, pulling the front of the display upwardly upon the hinge 54 and raising the back plate upon its hinge 65. Since this display pulls the opposite sides 56 inwardly, the openings 67 for the rubber band 66 may be located within the side edges of the bottom piece 52, and by crossing the strands of the rubber band, the opposite sides are pulled more tightly inward, thus completing the rounded front of the display figure.

As thus presented, it is apparent that surprise display devices of great variety may be presented operated by rubber bands, and providing different structures when set up, capable of being used for a wide variety of articles, particularly for advertising. The element of surprise added to the novelty of the structure will cause the device to be repeatedly operated, and to be retained and shown to a large number of people, thus adding to its value as an advertising device.

While two somewhat different constructions are shown, they should be regarded as illustrations rather than limitations of the invention, as various changes in the construction, combination and arrangement of the parts may be made without departing from the spirit and scope of the invention.

We claim:

1. A surprise display comprising a supporting flat base, a foldable display of sheet material having a front portion hinged to the base to swing uprightly, a top hinged to the front portion, sides hinged to the edges of the front portion and each side having angular hinged portions connecting it to the adjacent end of the top and these angular portions collapsing together when the display is distended, the sides and said angular portions foldable relatively inward of their connection with the display front when the display is collapsed, and an endless resilient band having opposite portions engaging the base and the top to swing the display upwardly with the top overlying the front and with intermediate portions of the band extending angularly so that one overlaps the other engaging the said sides and swinging them outwardly, collapsing the angular hinged portions together and swinging the sides outwardly to hold the front in erect position and to support the top in horizontal position and with the main portions of the resilient band enclosed by the connected front, top and side portions thus erected.
